UNITED STATES PATENT OFFICE.

CARL MAIER, OF BADEN, SWITZERLAND, ASSIGNOR TO THE FIRM OF BORSARI & CIE.,
OF ZOLLIKON-ZURICH, SWITZERLAND.

METHOD OF PRODUCING A CONTINUOUS SEAMLESS LINING ON CONCRETE WALLS IN
COURSE OF THEIR CONSTRUCTION.

1,175,163.

Specification of Letters Patent. Patented Mar. 14, 1916.

Application filed December 16, 1913. Serial No. 806,979.

To all whom it may concern:

Be it known that I, CARL MAIER, a citizen of the Republic of Switzerland, and a resident of Baden, Switzerland, have invented 5
5. a new and useful Method of Producing a Continuous Seamless Lining on Concrete Walls in Course of Their Construction, of which the following is a specification.
10 It is known to employ plates of asphalt and the like for covering concrete walls, and in particular for lining concrete tanks, which plates were secured to the finished concrete wall by means of cement plaster or the like, or attached to the concrete wall by placing 15 them into the molds for the concrete structures and thereupon filling in the concrete material.

Owing to the great fragility of the plates it was, in both instances, only possible to 20 use the plates of comparatively small dimensions, so that there were a large number of joints in the respective covering which had to be filled with molten asphalt or the like, if a continuous lining was to be produced.

The object of the present invention is to allow of the use of plates of any size, and 25 of providing a concrete wall with a lining consisting of one single piece, already during 30 the construction of such wall.

The present invention consists in connecting the plate of a size and shape corresponding to the concrete wall with the wall of the mold used for the construction of the concrete wall, and thereupon placing this mold wall together with the plate attached thereto into position, bracing it in the usual manner, and lastly filling up the cavity of the mold with concrete. When the concrete has 35 set, the bracing woods are removed, the connections between the liner plate and the mold wall detached and the latter is removed. The plate may be secured to the mold walls in various manner. So for instance a layer 40 of sand *b* is applied to a corresponding horizontal surface *a* (Figs. 1 and 2 of the accompanying drawing); on this layer of sand short pieces of iron *c* are placed at a pitch of about 1 meter, and around these pieces of 45 iron or the like a wire *d* is wound, so that its ends project upward. Then the asphalt or the like is poured onto this arrangement to the required thickness of the plate. After the plate *e* has set, it is laid on the wall *f*

of the mold and the ends of wire projecting 55 from the plate are passed through previously drilled holes and secured on the outside of the wall. The thus combined plates and walls are then used in the hereinbefore described manner for constructing the concrete 60 walls. The concrete *g* (Fig. 3 of the accompanying drawing) will adhere tightly to the cast plate *e*, as the latter contains the coarse grains of sand embedded in the contact surface, between which the concrete will enter. 65

When the concrete wall has been completed, the wires *d* holding the asphalt plate to the mold wall *f* are detached and preferably cut down flush with the concrete (Fig. 3) after the mold wall has been removed, whereupon the small holes produced are filled out with molten asphalt or the like. 70

Another method of carrying out the present invention is to pour the plate on the mold wall, which has been placed in a horizontal position and is smooth, while previous to this pouring nails or the like have been driven into it from the rear, so that they will project into the poured plate, and, after completion of the structure, may be 75 withdrawn again from the outside, thereby detaching the plate from the mold wall. 80

I claim:

1. A method of producing a continuous seamless lining on concrete walls in course 85 of construction, said lining being composed of fusible organic materials, said method consisting in forming a continuous seamless plate out of said organic materials for said lining, firmly securing said continuous seamless plate to the mold walls employed for 90 constructing the concrete walls, using the thus combined walls for the molds for pouring the concrete, and detaching the mold walls from the said continuous seamless lining plate, after the concrete has set. 95

2. A method of forming a continuous seamless lining on concrete walls in course 100 of their construction, said lining being composed of fusible organic materials, said method consisting in pouring fusible organic materials in their molten condition upon a coarse granular layer, permitting the said fusible organic materials to set, said combined plate being continuous and 105 seamless and molded to the shape of the said wall, firmly fastening said combined continuous seamless lining plate to the mold

walls employed for constructing the concrete walls, the said coarse granular layer being away from the said mold walls, using the thus combined walls for the mold for forming the concrete, and detaching the mold walls from the said combined plates after the concrete has set.

3. A method of producing a continuous seamless lining on concrete walls in course of their construction, the said lining being composed of fusible organic materials, said method consisting in firmly securing the plates forming the entire lining to the mold walls employed for constructing the concrete walls, said lining plates being provided with internal fastening means for fastening them to the said mold walls, using the thus combined walls for the molds for pouring the concrete, and disconnecting the said fastening means from the mold walls and removing the mold walls, after the concrete has set.

4. A method of producing a continuous seamless lining on concrete walls in course of their construction, said lining being composed of fusible organic materials, said method consisting in pouring the said fusible organic materials in a molten condition on bars of iron, so that said fusible organic materials when set are reinforced by said bars of iron, allowing said fusible organic materials to set, firmly securing the plate thus formed to the mold walls employed for constructing the concrete walls, using the thus combined walls for the mold for pouring the concrete, and detaching the said mold walls, after the concrete has set.

In testimony, that I claim the foregoing as my invention, I have signed my name in presence of two subscribing witnesses.

CARL MAIER.
